Application March 9, 1953, Serial No. 23,952

Term of patent 14 years

(Cl. D74—1)

To all whom it may concern:

Be it known that I, Hazel J. Hawkinson, a citizen of the United States of America and a resident of San Diego, State of California, have invented a new, original, and ornamental Design for a Copybook Holder, of which the following is a specification, reference being had to the accompanying drawing, forming a part hereof.

Figure 1 is an isometric view of my design for a copybook holder;

Figure 2 is an across-sectional view thereof, a notebook being shown in broken lines for purpose of illustration.

I claim:

The ornamental design for a copybook holder, as shown and described.

HAZEL J. HAWKINSON.
